MOVABLE RECLINING CHAIR WITH BACK-REST AND SEAT

Fridtjof F. Schliephacke, Berlin-Schmargendorf, Germany, assignor to Anton Lorenz, Boynton Beach, Fla.

Application October 24, 1956, Serial No. 618,043

7 Claims. (Cl. 155—106)

This invention relates to articles of furniture and more particularly to articles of repose for supporting the body of a person, wherein a seat and a back-rest being movable relative to each other may be brought from a sitting position into a reclined position and vice versa.

An object of the invention is to provide a reclining chair of above described type with an improved mechanism for controlling the movements of the back-rest and the seat in dependence on each other.

Another object of the invention is to provide a reclining chair of above described type with an improved mechanism for controlling the relative movements of the back-rest, the seat and a leg-rest.

A further object of the invention is to improve on the art of reclining chairs as now customarily made.

Other objects and structural details of the invention will be apparent from the following description when read in conjunction with the accompanying drawings forming part of this specification, wherein:

Fig. 1 is a side elevational view of a reclining armchair, according to the invention, a portion of a side wall being broken away,

Fig. 2 is a side elevational view of the chair shown in Fig. 1 wherein, however, the movable elements of the chair are in the extreme reclined position,

Fig. 3 is a side elevational view of a further embodiment of the reclining armchair, according to the invention, a portion of a side wall being broken away,

Fig. 4 is a side elevational view of the chair shown in Fig. 3 wherein, however, the movable elements of the chair are in the extreme reclined position,

Fig. 5 is a side elevational view of still another embodiment of a reclining chair according to the invention, a portion of a side wall being broken away, and

Fig. 6 is a side elevational view of the reclining chair shown in Fig. 5 wherein, however, the movable members of the chair are in the extreme reclined position.

Referring now to Figs. 1 and 2, 10 generally indicates a support having side walls 12 and 14 connected with each other by cross bars 16 and a rear wall 18.

A back-rest 20 is swingably mounted on the support 10 at 22. The rear portion of a seat 24 is pivoted to the back-rest 20 at 26. The pivotal connection 22 between the back-rest 20 and the support 10 is below the pivotal connection 26 between the seat 24 and the back-rest 20. A controlling member in the shape of a plate 28 is swingably mounted on the support 10 at 30. The rear end of a first controlling link 32 is pivoted to the seat 24 at 26 in coaxial alignment with the pivotal connection between the seat 24 and the back-rest 20. The front end of said first controlling link 32 is pivoted to the controlling member 28 at 34. The lower end of a second controlling link 36 is pivoted to the controlling plate 28 at 38. The upper end of said second controlling link 36 is pivoted to the seat 24 at 40.

Thus, upon a movement of the back-rest 20 from the sitting position shown in Fig. 1 into the reclined position

2

shown in Fig. 2 the controlling member 28 is swung by the first controlling link 32 from the position shown in Fig. 1 into the position shown in Fig. 2, and the seat 24 is brought through the medium of the second controlling link 36 into the position shown in Fig. 2. In other words, there is a coordination between the movements of the back-rest 20 and the seat 24 during a movement of said elements from the sitting position shown in Fig. 1 into the reclined position shown in Fig. 2 and vice versa.

The sitting position of the movable members of the chair is limited by a stop 42 attached to the support 10 for abutting engagement with the seat 24. The extreme reclined position of the movable members of the chair is limited by the upper edge 44 of the rear wall 18 co-operating with the back-rest 20.

The chair shown in Figs. 1 and 2 is equipped with a leg-rest 46.

The movements of said leg-rest 46 are controlled in dependence on the movements of the back-rest 20 and the seat 24 in the following manner: A first link 48 is swingably mounted on the seat 24 at 50. The rear end of a second link 52 is pivoted to the lower end of said first link 48 at 54 while the front end of said second link 52 is pivoted to the lower end of the leg-rest 46 at 56. The front end of a third link 58 is pivoted at 60 to the upper end of the leg-rest 46 at a point spaced from the pivotal connection 56 between the leg-rest 46 and the second link 52. The third link 58 is pivoted at 62 intermediate its ends to the first link 48. The pivotal connection 62 is spaced from the pivotal connection 54 between the first link 48 and the second link 52. The front end of a fourth link 64 is pivoted at 66 to the first link 48 at a point located between the pivotal connections 62 and 50 of said first link 48 with the third link 58 and the seat 24 respectively. The rear end of the fourth link 64 is pivoted to the controlling plate 28 at 68. The upper end of a fifth link 70 is pivoted at 72 to an intermediate point of the forth link 64 and the lower end of said fifth link 70 is pivoted at 74 to the rearwardly projecting end of the third link 58.

Thus, when during above described movement of the backrest 20 and the seat 24 from the sitting position shown in Fig. 1 into the reclined position shown in Fig. 2 the controlling plate 28 is swung about its pivot 30 on the support 10 from the position shown in Fig. 1 into the position shown in Fig. 2, the leg-rest is propelled forwardly and upwardly from the position shown in Fig. 1 into the position shown in Fig. 2 by means of above described link systems 48, 52, 58, 64 and 70 in dependence on the movements of the controlling plate 28 and the seat 24. Thus, there is a coordinated relationship between the movements of the back-rest 20, seat 24 and leg-rest 46 when said members are moved from the sitting position shown in Fig. 1 into the reclined position shown in Fig. 2.

According to the embodiment shown in Figs. 3 and 4 again the back-rest 120 is pivoted to the support 110 at 122 at a point below the pivotal connection 126 between the seat 124 and the back-rest 120.

Furthermore the controlling member 128 swingably mounted on the support 110 at 130 and its link connection 136 with the seat 124 corresponds fully to the arrangement of the controlling member and the second link according to the embodiment shown in Figs. 1 and 2. Moreover, again the front end of a first controlling link 132 is pivoted to the swingable controlling plate 128 at 134. The rear end of said first controlling link 132 at 127 is pivoted to the seat 124 at 127 at a point spaced from the pivotal connection 126 between the seat 124 and the back-rest 120.

The arrangement of the leg-rest 146 and its controlling

mechanism 148, 152, 158, 164 and 170 and the connection of the latter with the seat 124 and the controlling member 128 respectively corresponds fully to the leg-rest control of the embodiment shown in Fig. 1.

When the back-rest 120 is swung about its pivot 122 from the upright position shown in Fig. 3 into the reclined position shown in Fig. 4, the seat 124 and the leg-rest 146 are positively moved from the position shown in Fig. 3 into the position shown in Fig. 4 through the link mechanism described above.

According to the embodiment shown in Figs. 5 and 6 again the lower end of the back-rest 220 is swingably mounted on the support 210 at 222 at a point below the pivotal connection 226 between the seat 224 and the back-rest 220.

The arrangement of the controlling member 228 is somewhat different from the arrangement of the corresponding controlling member of the embodiments shown in Figs. 1-4. According to Fig. 5 the controlling member is swingably mounted on the support 210 at 230. The pivotal connections 234 and 238 of the controlling member 228 with the first controlling link 232 and the second controlling link 236 respectively are above and to the left of the pivotal connection 230 between the support 210 and the controlling member 228 when the latter is in the position shown in Fig. 5. The rear end of the first controlling link 232 is pivoted to the back-rest 220 at 229 at a point spaced from the pivotal connection 226 between the back-rest 220 and the seat 224. The upper end of the second controlling link 236 is pivoted at 240 to the seat 224. It will be readily understood that upon a movement of the back-rest 220 from the upright position shown in Fig. 5 into the reclined position shown in Fig. 6 the controlling member 228 is swung about its pivot 230 from the position shown in Fig. 5 into the position shown in Fig. 6. This swinging movement of the controlling member 228 furthermore results in a forward and upward movement of the leg-rest 246 connected with said controlling member 228 and the seat 224 through the links 248, 252, 258, 264 and 270 in the same manner as described above in connection with the embodiments shown in Figs. 1-4.

Thus, the embodiment shown in Figs. 5 and 6 likewise provides for coordinated movements of the back-rest 220, seat 224 and leg-rest 246 between a sitting position and reclined position. The sitting position is limited by the abutting engagement of the seat 224 with the stop 242 while the extreme reclined position is limited by the abutting engagement of the back-rest 220 with the upper edge 244 of the rear wall 218 of the support 210.

I have described preferred embodiments of my invention but it is understood that this disclosure is for the purpose of illustration and that various omissions or changes in shape, proportion and arrangement of parts, as well as the substitution of equivalent elements for those herein shown and described may be made without departing from the spirit and scope of the invention as set forth in the appended claims.

What I claim is:

1. An adjustable reclining chair comprising a support, body supporting means including a back-rest and a seat, pivot means mounting said back-rest on said support for movement of said back-rest from an upright position to a rearwardly-tilted reclining position, said seat being pivotally connected at its rear end to said back-rest at a point above said pivot means for rearward movement of said seat when said back-rest is tilted rearwardly about said pivot means, a controlling member pivotally mounted on said support, a first controlling link pivotally connected at one end to said body-supporting means at a point above said pivot means whereby the first controlling link is moved rearwardly with body-supporting means, the other end of said first controlling link being pivotally connected to said controlling member for pivoting said controlling member about its pivotal mount on the support when the first controlling link is moved

rearwardly, and a second controlling link pivotally connected to the forward end portion of the seat and to the controlling member at a point spaced from the pivotal mount of the controlling member on the support for raising said second controlling link and lifting the forward end of the seat when the controlling member is pivoted by rearward pulling movement of the first controlling link, the pivotal connection of the first controlling link to the controlling member being located between the pivotal mount of the controlling member on the support and the pivotal connection of the second controlling link to the controlling member.

2. An adjustable reclining chair according to claim 1 in which the first controlling link is pivoted to the seat at a point in coaxial alignment with the pivotal connection between said seat and said back-rest.

3. An adjustable reclining chair according to claim 1 in which said first controlling link is pivoted to the back-rest at a point spaced from the pivotal connection between said seat and said back-rest.

4. An adjustable reclining chair comprising a support, body-supporting means including a back-rest and a seat, pivot means mounting said back-rest on said support for movement of said back-rest from an upright position to a rearwardly-tilted reclining position, said seat being pivotally connected at its rear end to said back-rest at a point above said pivot means for rearward movement of said seat when said back-rest is tilted rearwardly about said pivot means, a plate having a pivotal mount on said support, a first controlling link pivotally connected at one end to said body-supporting means at a point above said pivot means whereby the first controlling link is moved rearwardly with body-supporting means, the other end of said first controlling link being pivotally connected to said plate at a point beneath and forwardly of the pivotal mount of said plate on said support for pivoting said plate about its pivotal mount when the first controlling link is moved rearwardly, and a second controlling link pivotally connected to the forward end portion of the seat and to the plate at a point beneath and rearwardly of said pivotal mount of the plate on the support for raising said second controlling link and lifting the forward end of the seat when the plate is pivoted by rearward pulling movement of the first controlling link.

5. An adjustable reclining chair comprising a support, body-supporting means including a back-rest and a seat, pivot means mounting said back-rest on said support for movement of said back-rest from an upright position to a rearwardly-tilted reclining position, said seat being pivotally connected at its rear end to said back-rest at a point above said pivot means for rearward movement of said seat when said back-rest is tilted rearwardly about said pivot means, a plate having a pivotal mount on said support, a first controlling link pivotally connected at one end to said body-supporting means at a point above said pivot means whereby the first controlling link is moved rearwardly with body supporting means, the other end of said first controlling link being pivotally connected to said plate at a point above and forwardly of the pivotal mount of said plate on said support for pivoting said plate about its pivotal mount when the first controlling link is moved rearwardly, and a second controlling link pivotally connected to the forward end portion of the seat and to the plate at a point above the pivotal mount and forwardly of the connection of the first controlling link to the plate for raising said second controlling link and lifting the forward end of the seat when the plate is pivoted by rearward pulling movement of the first controlling link.

6. An adjustable reclining chair comprising a support, body supporting means including a back-rest and a seat, pivot means mounting said back-rest on said support for movement of said back-rest from an upright position to a rearwardly-tilted reclining position, said seat being pivotally connected at its rear end to said back-rest at a point above said pivot means for rearward movement of said seat when said back-rest is tilted rearwardly about said pivot means, a plate having a pivotal mount on said support, a first controlling link pivotally connected at one end to said body-supporting means at a point above said pivot means whereby the first controlling link is moved rearwardly with body-supporting means, the other end of said first controlling link being pivotally connected to said controlling member for pivoting said controlling member about its pivotal mount on the support when the first controlling link is moved

totally connected at its rear end to said back-rest at a point above said pivot means for rearward movement of said seat when said back-rest is tilted rearwardly about said pivot means, a controlling member pivotally mounted on said support, a first controlling link pivotally connected at one end to said body-supporting means at a point above said pivot means whereby the first controlling link is moved rearwardly with body supporting means, the other end of said first controlling link being pivotally connected to said controlling member for pivoting said controlling member about its pivotal mount on the support when the first controlling link is moved rearwardly, a second controlling link pivotally connected to the forward end portion of the seat and to the controlling member at a point spaced from the pivotal mount of the controlling member on the support for raising said second controlling link and lifting the forward end of the seat when the controlling member is pivoted by rearward pulling movement of the first controlling link, a leg-rest, a leg-rest linkage mounting said leg-rest on the forward end of said seat for swinging movement of said leg-rest between a retracted position beneath the seat and an extended position forwardly of said seat, and link means connecting said controlling member with said

leg-rest linkage for actuation of the latter in response to pivoting movement of the controlling member.

7. An adjustable reclining chair according to claim 6, in which the leg-rest linkage includes a first link pivoted to the seat, a second link pivoted to the leg-rest and to said first link, a third link pivoted to said leg-rest and to said first link at points spaced from the pivotal connections of the second link with said leg-rest and said first link, said link means comprising a fourth link pivoted to said controlling member and said first link, and a fifth link pivoted to said fourth link and said third link.
